COMBINED UNDERGARMENT AND
ABDOMINAL SUPPORT

Isidor Rosenfeld, New York, N. Y.

Application April 7, 1934, Serial No. 719,498

1 Claim. (CL 2-27)

My invention relates to combined undergarments and abdominal supporters, and particularly to supports embodied in undergarments, such as the corset, corselette, girdle, surgical belt and surgical corset, etc.

Originally, undergarments of the corsets and corselette type were designed and intended mainly to give shape to the body of the wearer in accordance with the dictates of fashion, and only 10 incidentally to provide support therefor. To a very great extent, however, this secondary purpose has been completely lost sight of, and it is an object of my invention, therefore, to provide 15 an undergarment for supporting the body of the wearer and particularly the abdominal regions thereof.

It is a further object of my invention to provide a device of the character specified which will not only support the abdominal regions, but also 20 serve to mold and shape same.

Another object of my invention is to provide a device of the character specified which will support and mold the abdominal regions without placing same under unduly artificial or painfully 25 restrictive stresses.

Further objects of my invention will in part be apparent, and in part be pointed out hereinbelow.

In the drawing annexed hereto for illustrative 30 purposes only, Fig. 1 is a perspective of one form of device (corselette) constructed according to and embodying my said invention;

Fig. 2 is a side elevation thereof with the normal condition of the abdominal regions shown 35 in outline;

Fig. 3 is an enlarged detail view of the front central section; and

Fig. 4 is a section thereof on the line 4-4 of Fig. 3, similarly enlarged.

The corselette shown in the drawing—the device of my invention is being shown embodied in this type of undergarment merely for illustrative purposes only, and because the corselette is one of the most common of all feminine undergarments—comprises side, front, back and brassière portions. Broadly speaking, this is conventional, since all these portions, or equivalents thereof, are contained within every corselette, but it is in the particular construction and arrangement 45 of certain portions thereof in the device of my invention that I depart from the conventional and achieve results not attainable by those devices now in common use.

Corselette 10 is of the "wrap-around" type; that 50 is, when being put on, the garment is wrapped

around the body of the wearer and the end edges thereof fastened in the rear, usually by laces, although other fastening means may be employed, and the device comprises bust support, or brassière portion, 12, held in place on the body 14 5 of the wearer by shoulder straps 16 fitting over the shoulders. Support 12 extends entirely across the front of the body, from under one armpit to the other, and at the side edges 18 thereof is secured to back portions 20. Body portion 22 also 10 extends entirely across the front of the body from under one armpit to the other, and is secured by its upper edge 24 to the lower edge of bust support 12, and at the side edge 26 thereof to back 20, just below edge 18. Body 22 extends from the 15 bust support 12 downwardly to just below the abdomen, the lower edge 28 of said body portion 22 following a substantial U-shaped curve, the "prongs" flaring upwardly and outwardly to exaggerate the U-curvature (see Fig. 3). 20

A pair of downwardly depending front portions 30 are secured to body 22 at the lower sides of edge 28, as at 31, and a pair of side portions 32 are secured to said body 22 at the upper sides of edge 28 as at 33. The front portions 30 are 25 designed to fit over and around the front of the thigh, and the side portions fit over the hip and side of the thigh. A wedge-shaped space between the front and side portions 30 and 32 is filled by portion 34 of elastic material, which is secured to 30 the spaced apart edges of said portions.

A number of back portions 20 are secured to each other, as at 21 (Fig. 2), to the device, at each side thereof; to bust support 12, as at 18; to body portion 22, as at 26; and to side portion 35 32, as at 36, and the endmost of said back portions on each side are laced together, in the rear (not shown) to fasten the corselette onto the body of the wearer.

Body portion 22 is composed of an originally 40 flat blank of fabric 38 considerably wider at the bottom than at the top. A number of "darts" 40 are cut in each lateral side of the blank. Each "dart" constitutes the removal of a substantially 45 wedge-shaped portion of material from the side of the strip, forming a strap 42, and the darts are of such size that the lowermost strap 42 is longer than the one immediately above it. As in Fig. 3, the darts extend inwardly but about one-third of the width of the blank, and when the proximate 50 edges of the straps are sewed together, as at 44, Figs. 3 and 4, restricting or gathering in the sides of the blank, a pocket-recess 46 is formed. For convenience, I shall refer to this process— 55

that of removing darts and sewing the strap edges together—as puckering.

To supplement pocket 46 in its supporting action, as will be explained in detail below, I 5 provide a sub-body member 48 laterally coextensive in width with said pocket, but not necessarily as long, composed of alternating strips 50 of elastic material between strips 52 of non-elastic fabric material. As a unitary whole, 10 therefore, this member 48 is horizontally expansible. Member 48 is secured to the inside of portion 22 along the coextensive side and lower edges thereof, as at 54 and 56 respectively. The words "laterally is extensive" are used by 15 me, in this description of my device, and in the appended claim, to describe the relations between body member 22 and sub-body member 48. Both are of the same width though of different length and are secured together by their side 20 and bottom edges. Normally, therefore, they will each extend across from side to side of the device.

The device operates in a two-step manner. When same is put on, member 48 first comes into contact with the prolapsed abdominal 25 regions, and as the lacings on the garment are pulled tighter and tighter, the abdomen is lifted inwardly. At the same time, member 48 expands laterally, until when the lacing is completed the body portion 22 is contacted by the sub-body 30 member. Body portion 22 is not expansible, and the pocket 26 therein receives and supports the abdominal regions in the inwardly lifted position thereof.

My device is adapted, and particularly fitted, 35 for those women with prolapsed abdominal regions (see dot-and-dash line, Fig. 2). This particular condition is particularly prevalent in larger women and is a constant source of difficulty and annoyance. With my improved under- 40 garment support of such character is given to

the prolapsed regions as to do away with any and all need for the various types of abdominal belts usually used together with the usual type of undergarment.

The benefits derived from use of my device are 5 obvious. First and foremost, the pocket into which the prolapsed and protruding abdominal regions are received provides sure, adequate and comfortable support therefor. Secondly, the inner, expansible member 48, in addition to operating 10 as a pocket reinforcer, imparts some degree of molding to the body. The device is light, as all the parts thereof, body portion, front, side, back and brassière portions, are of fabric material. The elastic portions 50 and 34 are also 15 fabric interwoven, and add only slightly to the weight of the garment as a whole. No straps, belts, buckles, etc. are needed with my device, and with same, not only is a safe, sure and efficient support provided, but some definite degree 20 of molding or shaping is imparted to the body of the wearer.

Having now described my invention, what I claim and desire to secure by Letters Patent is:

A device of the character described comprising 25 a body member, laterally expansible means on the inner side of said body member for elevating and placing the abdominal regions to be supported under restrictive stresses, and means on and part of said body member proper comprising 30 a receptacle integral with said body member for receiving and securing inside said receptacle said abdominal regions in the elevated and supported position, the side portions of said body member being puckered to define the limits of said last 35 named means, said inner member being attached to said body member along its side and bottom edges.

ISIDOR ROSENFELD.
